(57) **CLAIM**

The ornamental design for an VR headset, as shown and described.

DESCRIPTION

FIG. 1 is a perspective view of an VR headset showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the VR headset where the VR headset is in a configuration of use.

The broken lines in FIG. 9 depict environment that form no part of the claimed design. The other broken lines in the drawings depict portions of the VR headset that form no part of the claimed design.
